UNITED STATES PATENT OFFICE.

FRED M. YOUNG, OF RACINE, WISCONSIN, ASSIGNOR TO RACINE RADIATOR COMPANY,
OF RACINE, WISCONSIN, A CORPORATION OF WISCONSIN.

METHOD OF ASSEMBLING RADIATORS.

Application filed March 14, 1924. Serial No. 699,157.

This invention relates mainly to automobile radiators and especially to improved methods and means for mounting same on the front end of the chassis. Heretofore, 5 so far as I am aware, detachable brackets only have been used to support these radiators, but such means have been a source of much trouble, inconvenience and expense. Such brackets are usually held in place by 10 screws engaging cast blocks set inside the tank or reservoir chamber. I aim to eliminate both the blocks and the screws.

The main objects of this invention are to provide an improved form of radiator 15 hanger bracket and method of attaching same; to provide a combined radiator and bracket of unitary and substantially integral character; to provide for a lighter construction of bracket without diminution of 20 strength and resilience; to provide for riveting the bracket to the radiator tank without hindrance to subsequent assemblage and proper sealing of the core-tank joints of the radiator adjacent to the bracket; to 25 provide for bending the bracket into final shape after riveting in place and after sealing of the joints; to so simplify and unify the construction that mounting and de- 30 mounting may be more readily accomplished.

An illustrative embodiment of this invention is shown by the accompanying drawings in which:—

Figure 1 is a front view of a radiator with the casing shell in place and with the 35 chassis side bars shown in cross section.

Fig. 2 is a similar view with the chassis bars omitted and with the supporting brackets shown in their initial divergently extended joint sealing position, prior to 40 bending upward into final shape.

Fig. 3 is a slightly enlarged fragmentary detail of the lower left hand corner with the shell removed and with the bracket disposed outwardly substantially as in Figure 45 2, the side portion of the shell and adjacent part of said bracket being indicated by dotted lines as they appear in their finished normal position.

Fig. 4 is a much enlarged plan of one 50 of the bracket blanks prior to bending, and showing two rivet holes and a bolt hole.

In the construction shown in the drawings, the radiator 1 as a whole is supported on resilient brackets 2 bolted by the side

bars 3 of the chassis, the brackets being 55 fastened directly on the bottom tank of the core of the radiator, as shown in Fig. 3.

Said radiator comprises mainly a ventilating core 4 in substantially integral combination with upper and lower bulk heads 60 5 and 6 respectively, the latter serving as a tank or reservoir for the water supply, the said members 4, 5, and 6 being joined together and hermetically sealed as shown by the lower horizontal sealing line 7 on 65 Figures 2 and 3 as usual in such devices.

The radiator casing shell 8 is in place and is shown by full lines on Figures 1 and 2, and is preferably fastened to the core in any well known manner. The side part 70 8' of the shell is spaced somewhat from the side part 4' of the core as shown at 9 on Figure 2.

In order to simplify the construction and the method of assembling these radiators, 75 the bracket 2 is first formed from a blank 10 shown in Figure 4 into the form substantially as shown in Figures 2 and 3, and is riveted directly and permanently to the bottom of the reservoir 6 before the latter 80 is connected to the core 4, ready access thus being had to the interior of said reservoir for setting the rivets 11, since the reservoir is then open at the top. A bolt hole 10' and rivet holes 10" are provided in said 85 blank.

The purpose of adopting the initial form of the bracket shown in Figures 2 and 3 is to permit ready access to the abutting edges 90 of the reservoir 6 and the core 2 along the sealing line 7, especially at the sides, as indicated at 7'. This permits the radiator assembling operator to get at the joint back of the brackets 2 or between the bracket and the reservoir with a soldering iron, or 95 the like, in a manner which is not possible with the usual form of brackets after the latter are attached. It is preferable to use an external soldered joint, which can be repaired from the outside, and it is accordingly necessary to solder all around the joints between the brackets and the tank to 100 stop any possible leakage through the rivet holes. Then the joint 7 is sealed after the bracket is riveted to the tank 6 and while 105 the brackets are positioned as shown in Figures 2 and 3, after which the free ends of the bracket are swung inwardly about the

bending point 12 so as to fit snugly against the casing part 8', the latter being readily demountable and interchangeable.

In order that the radiator core may be protected from injurious vibration such as might result from violent jolts the brackets 2 are formed of resilient material and are sufficiently yielding to materially cushion the core. With this end in view, the blanks 10 10 are formed as shown in Figure 3 with a medial reverse curve offset at 13 which provides for spacing the upper part of the bracket somewhat away from the core and casing as indicated at 14 on Figure 1. The 15 upper tip of the bracket is bent at a right angle at 15 so as to provide a horizontal lug 2' adapted to receive the bolt 16 which secures the bracket to the chassis bar 3. In order to insure clearance for the lower part 20 of the shell side part 8' an outward bulge is formed in the bracket at 17 just above the bend point 12. When the device is assembled the bracket is finally bent inward, the bending occurring naturally at point 12 25 where it bears against the corner of the reservoir and the outward bulge 17 serving to provide the necessary clearance spacing as above explained and as shown in Figures 2 and 3. The bracket bends and curves are preferably formed on a mandrel as this insures precision and uniformity. The apertured lug 18 on the lower edge of the casing accommodates the engine crank shaft extension as will be understood.

35 It will be observed that the spacing 14 provides for horizontal cushioning and the medial offset at 13 provides for vertical or gravity cushioning. Moreover, this construction simplifies the design in that it reduces the number of parts, screw seating

blocks being eliminated, and the core is made permanently unitary and substantially integral with the core support brackets.

Although but one specific embodiment of this invention has been herein shown and described it will be understood that numerous details of the construction shown may be altered or omitted without departing from the spirit of this invention as defined by the following claims. 50

I claim:

1. The method of assembling a radiator core, water tank and support brackets for a motor vehicle, which consists in riveting the brackets to the exterior of the bottom of the water tank, the brackets then being in a form to extend away from the sides of the tank, then attaching the core to the top of the water tank and externally soldering the joints between the brackets and the water tank, and finally bending the brackets inward convergently adjacent to the sides of the tank and co-assembled core into the form required for ultimate installation. 55

2. The method of fabricating automotive vehicle radiators, which consists in riveting supporting brackets to the bottom of the water tank, with the outward ends of the brackets extending divergently from the sides of the tank, then attaching the radiator core to the top of the water tank and externally sealing the joints between the brackets and the tanks by soldering, then bending the extending ends of the brackets 70 up alongside the sides of the core, and then 75 attaching the shell to the core.

Signed at Chicago this 28th day of December 1923.

FRED M. YOUNG.
